UNITED STATES PATENT OFFICE.

JOHN MAGEE, OF DETROIT, MICHIGAN, ASSIGNOR TO DIAMOND POWER SPECIALTY COMPANY, OF DETROIT, MICHIGAN, A CORPORATION OF MICHIGAN.

BLOWER FOR WATER-TUBE BOILERS.

1,150,138.

Specification of Letters Patent. Patented Aug. 17, 1915.

Application filed March 4, 1915. Serial No. 12,074.

To all whom it may concern:

Be it known that I, JOHN MAGEE, a citizen of the United States of America, residing at Detroit, in the county of Wayne and State of Michigan, have invented certain new and useful Improvements in Blowers for Water-Tube Boilers, of which the following is a specification, reference being had therein to the accompanying drawings.

10 In the operation of boilers having oppositely oblique sets of water tubes it is found advantageous to keep said tubes clean by the use of multiple jet pipes that are so disposed in the natural spaces of the boiler that

15 jets of steam may be projected along and across and through both sets of pipes and over the interior surfaces on which the gases of combustion are liable to deposit soot, light ash and other matter deleterious to

20 the conductivity of the walls and tubes and the general operation and efficiency of the boiler.

This invention relates to a soot blower for water tube boilers having sets of pipes or water tubes that are arranged in oppositely oblique relation and are usually staggered or alternated in position.

The invention consists in the matters hereinafter set forth and more particularly pointed out in the appended claims.

In the drawings, Figure 1 is a view in vertical section across a boiler of the type described, equipped with a blower that embodies features of the invention; Fig. 2 is

35 a view in longitudinal section of the boiler, and Figs. 3 and 4 are views in detail of brackets for supporting blower units from the water tubes.

In the drawings, a boiler is illustrated having a pair of headers 1 and 2 interconnected by water tubes 3 that are in alternate arrangement to another set of water tubes 4 of opposite inclination, which connect other headers 5 and 6. The headers are appropriately connected to a steam dome 7 and mud drums 8 or the like, and are arranged in a suitable setting 9 over the combustion chamber 10 and grate bars 11 of the boiler furnace. As a result there are angular spaces at the corners between the outer tubes of the two sets which afford natural cleaning spaces in which blower units may be advantageously placed. In order to clean the upper space effectively, a jet pipe 12 is extended across the boiler transversely to the

tubes of both sets on which it is supported as by appropriate brackets indicated at 13. Such tubes have lateral jet openings or jet nozzles 14 which may be of the Venturi blower type, and may as herein indicated be 60 jacketed or incased with a heat protecting lining 15 and outer casing 16, or the jet pipe may be water jacketed or air cooled or otherwise arranged to resist high temperature. At the ends, appropriate housings 19 and 20 are employed that are mounted in the boiler setting walls as bearings for the jet pipes, a steam pipe 21 leading either from the boiler itself or some other suitable source of supply, (or it may be a line from a 65 source of air under pressure) is connected through a suitable fitting 22 with the pipe while a wheel 23 to which a sprocket chain may be applied as desired, affords means for turning the pipe in all directions. As a 70 result jets may be made to sweep across and along and between the tubes in the direction of length as well as transversely thereto while they may also be made to impinge 75 against and between the surfaces that deline the gas passes of the boiler. In addition to this pipe 12 other jet pipes may be employed and such are shown at 26 and 27. These are similar in all respects to the pipe 12 and are mounted in a similar manner. 80 Of course the upper units 12 may be left out and the lower unit only employed or all three may be used as herein shown. 85

As a convenient means for supporting the pipes rotatably on the water tubes, bearings which may be easily alined may be employed. As one preferred form, the bearing 13 which is shown in detail in Figs. 3 and 4 is used, in which a bridge member 28 with companion clip 29 span a pair of water tubes, being retained by a clamping bolt 30. The member 28 has a pair of screw threaded studs 31 on which the half members 32 of a bearing are adjustably secured between jam nuts 33, so that they embrace the casing 16 of the 100 boiler tube 12.

As a result of this construction, a soot blower is obtained that readily cleans boilers of this description and is readily mounted thereon because of the ease of adjustment of the bearing members and the utilization of the natural spaces of the boilers in which to place the tubes. The multiple jet effect sweeps the soot from all parts of the boiler and thereby avoids the necessity of use of 110

the unwieldy hand blower and its inconvenience.

Obviously, changes in the details of construction may be made without departing 5 from the spirit of my invention and I do not care to limit myself to any particular form or arrangement of parts.

What I claim is:—

1. In a boiler having sets of water tubes disposed transversely to each other in oblique relation and a setting therefor, means disposed transversely to the tubes in the angular spaces formed between the sets and adapted to direct cleaning jets across, between and along the tubes of the sets adjacent the angles and over the interior surfaces of the boiler.
2. In a boiler having obliquely disposed sets of water tubes in oppositely arranged, transverse relation, jetting means mounted at the angles formed by the oppositely disposed sets and arranged to direct cleaning jets across and along and between the portions of the tubes of the several sets adjacent the angles and against and over the interior surfaces of the boiler.
3. In a boiler having a pair of oppositely inclined transversely disposed sets of water tubes, jet pipes rotatably mounted at the angles formed by the sets and adapted to direct cleaning jets across and along and between the portions of the tubes of the sets

adjacent the angles and the inclosing surfaces of the boiler.

4. In a boiler having a pair of oppositely inclined transversely disposed sets of water tubes, means for confining and directing the gases of combustion of the furnace of the boiler over the tubes, rotatable jet pipes in the angles formed between the tubes of the companion sets, means rotatably supporting the pipes on the water tubes, and means for manipulating the jet pipes for directing cleaning jets therefrom across, along and between the portions of the water tubes adjacent the angles and the interior surfaces of the inclosing means.

5. In a boiler having inclined water tubes, jetting means rotatably secured in operative relation to the pipes and means forming 50 bearings for the jetting means each consisting of a bridge member adapted to span a pair of water tubes, a companion clip therefor adapted to span a pair of water tubes, a clamping bolt securing the clip and bridge 55 member, bearing members embracing a jet pipe, and adjustable supporting means on the bridge member for the bearing members.

In testimony whereof I affix my signature in presence of two witnesses.

JOHN MAGEE.
